UNITED STATES PATENT OFFICE.

JAMES A. WATT, OF BROOKLYN, NEW YORK.

WATER-CLOSET VALVE.

Application filed November 22, 1921. Serial No. 516,967.

To all whom it may concern:

Be it known that I, JAMES A. WATT, a subject of the King of Great Britain, residing at Brooklyn, in the county of Kings and 5 State of New York, have invented certain new and useful Improvements in Water-Closet Valves, of which the following is a specification.

10 My invention relates to float valve for controlling the discharge of water from cisterns as are used in connection with water closets.

15 The principal object of my invention is to provide a float valve for this purpose which shall be extremely simple and efficient in its construction and operation, one in which the part, which is most likely to become defective through age or wear, may be easily renewed, one which can be manufactured at an extremely low cost and which 20 will be especially well adapted for assembling.

25 Another very important object of the invention is to construct a device of this nature whereby the yieldable portion of the float valve may be moulded instead of formed by a blowing process as is the common practice at the present time, thereby greatly reducing the cost of manufacture and increasing 30 the efficiency and accuracy of this portion.

35 Another important object of the invention is to construct a float valve, of this nature having all of the advantages found in the common or conventional float valve now extensively in use wherein the entire valve is made of yieldable material, usually rubber.

40 A very special feature of my invention consists in the provision of an efficient and effective clamping mechanism for grasping the edge of the flexible portion of the valve.

45 With the above and numerous other objects in view, as will appear as the description progresses, this invention resides in certain novel features of construction, and the combination and arrangement of parts as will be hereinafter more fully described and claimed.

50 In the drawings, Figure 1 is a vertical mid-section of my improved device, illustrating the preferred embodiment thereof,

Figure 2 is an enlarged detailed section showing the manner in which the clamping device grasps the flexible member,

55 Figure 3 is an enlarged detailed section showing the manner in which the two clamping sections are drawn together and

Figure 4 is a section taken on the line 4-4 of Figure 3.

Referring to the drawings in detail it will 60 be seen that the float valve consists of a cup-shaped seating member of yielding material 1 which is provided at its edge, with a flange 2 of yielding material preferably 65 conical shaped and an inverted cup-shaped stiffening and supporting member of rigid material in the form of a clamping mechanism consisting of a pair of conical shaped clamping members or cups 3 and 4.

The clamping member or cup 3 is disposed 70 so that its lower or larger end fits within the flange 2. It is to be noted that the diameter of this end of the clamping member or cup 3 is substantially larger than the diameter of the opening formed by the conical shaped 75 flange 2.

An annular groove 5 is preferably arranged on the exterior of the clamping member or cup 3 adjacent its base edge and a bead 6 is provided on the interior of the conical shaped flange 2. This bead 6 aids in holding the inner clamp 3 in proper relation 80 to the flange 2 while assembling the various parts.

The outer clamping member or cup 4 is 85 placed over the inner clamping member or cup 3 so that an aperture in its apex registers with an aperture in the apex of the inner clamping member or cup 3. A lug 7 including a head 7-a and a shank 7-b is positioned 90 so as to have its shank pass through these apertures in the clamping members or cups and a nut is within the clamping member or cup 3 for receiving this shank. This lug 7 is provided with an external thread so as to 95 receive the nut 8, which is preferably conical shaped, whereby the two clamping members or cups may be drawn tightly together so as to firmly and positively grip and clamp the flange 2 between their walls as is shown to 100 advantage in Figure 2 and it is to be noted that this clamping action takes place a distance from the edge of the cup-shaped seating member 1 that is at the juncture of flange 2 with seating member 1, or at a point 105 within the diameter of the edge of the cup-shaped seating member 1. It is also to be noted that the base edge of the inner clamp-

ing member or cup 3 is situated closer to the edge of the body 1 than is the base edge of the outer clamping member 4 thereby allowing the desired yieldability in the seating member 1 the same as though the entire valve were made of yieldable material as those which are now commonly in use.

10 A washer element 10 is preferably disposed between the clamping members 3 and 4 at their apexes thereby causing a locking action between the shank of the lug 7 and nut 8. The shank on the lug 7 is provided with a bore interiorly threaded for receiving the valve stem which may be of any preferred or conventional construction.

15 While I have illustrated and described my invention with some degree of particularity, I realize that in practice various alterations therein may be made. I therefore reserve 20 the right and privilege of changing the form of the details of construction or otherwise altering the arrangement of the correlated parts without departing from the spirit of the invention or the scope of the appended 25 claims.

Having thus described my invention, what I claim as new, and desire to secure by United States Letters Patent is:

1. A valve for flush tanks comprising a 30 cup-shaped seating member of yielding material and an air-tight inverted cup-shaped stiffening and supporting member of rigid material, a flange of yielding material formed on the edge of the cup-shaped seating member, said air-tight inverted cup-shaped stiffening and supporting member being attached to said flange a distance from the edge of said cup-shaped seating member, and the said stiffening and supporting mem-

ber provided near its center with means for 40 attaching it to a lifting rod.

2. A valve for flush tanks comprising a cup-shaped seating member of yielding material and an air-tight inverted cup-shaped 45 stiffening and supporting member of rigid material, a flange of yielding material disposed on the edge of the cup-shaped seating member, said inverted cup-shaped stiffening and supporting member being removably united to the flange a distance from the edge 50 of the cup-shaped seating member, and the said stiffening and supporting member provided near its center with means for attaching it to a lifting rod.

3. A valve for flush tanks comprising a 55 cup-shaped seating member of yielding material provided with a peripheral flange, and an air-tight inverted cup-shaped stiffening and supporting member of rigid material engaging said flange a distance from the 60 edge of said cup-shaped seating member, and the said stiffening and supporting member provided near its center with means for attaching it to a lifting rod.

4. A valve for flush tanks comprising a 65 cup-shaped seating member of yielding material provided with a peripheral flange, and an air-tight inverted cup-shaped stiffening and supporting member of rigid material including a pair of superimposed cup-shaped 70 members adapted to engage said flange a distance from the edge of the seating member, and the said stiffening and supporting member provided near its center with means for attaching it to a lifting rod.

75 In testimony whereof I affix my signature.

JAMES A. WATT. [L.S.]
